UNITED STATES PATENT OFFICE.

KARL E. PEILER, OF WEST HARTFORD, CONNECTICUT.

FEEDING MOLTEN GLASS.

Application filed January 28, 1926. Serial No. 84,495.

This application is mainly a division of my copending application for Letters Patent filed May 5, 1919, Serial No. 294,792 and is filed for the purpose of claiming certain features disclosed in the original application, particularly the control of the shape of mold charges of molten glass, produced and severed in suspension below a discharge outlet, by controlled interaction between the shears which sever the glass and the glass that is being severed. Such controlled interaction between the shears and the glass may be produced by raising the glass past the severing plane while the shears are cutting through the glass, by altering the cutting speed of the shears, causing the speed of the shear blades to change while they are passing through the glass, or by a combination of these operations.

Certain of the claims in this application are also readable upon my earlier application for Letters Patent filed December 4, 1916, Serial No. 134,828, and therefore this application is to be considered as a continuation of that earlier application as to all subject matter common to the two applications Serial No. 134,828 and Serial No. 294,792.

The present application is largely concerned with the shaping of the lower ends of the mold charges by causing the column of glass which connects each mold charge with the parent body of glass to move upwardly during part or all of the time when the glass column is being severed. By thus causing the severing means to operate in co-action with the rising movement of the glass adjacent to the severing means, the stub of glass which remains above the shears after severing is given a generally tapered, rounded or conoidal shape, and this severed and shaped stub forms the lower end of the next succeeding mold charge. This co-action between the shears and the rising glass may be termed a "whittling" action, by analogy with the whittling of the end a wooden stick by means of a knife.

By varying the speed at which the column of glass is lifted, the speed at which the shears are advanced to sever the glass, the extent to which the shear-speed is retarded as the shears cut through the glass, the position at which the shears are set, or the

relative timing of the lifting and shearing operations, or by combinations of these changes, a wide variety of shapes may be imparted to the lower ends of the mold charges, and such shapes may be conoidal, rounded, shouldered or of ogee outline, as will more fully appear below.

The ultimate object of the present invention, like that of the parent application, Serial No. 294,792, is to produce mold charges shaped, as closely as may be, to the shapes of the cavities of the molds in which the mold charges are to be received. It is a general rule in feeding molten glass that the best shaped together or mold charge is the one that does the least settling when it reaches the mold. Consequently, a charge is preferred which is similar in contour to the mold cavity, since the glass is then deposited in the mold with a minimum amount of settling. The lower portions of the cavities of glass molds are commonly more restricted than the body portions of the cavities, and the restricted lower portions have various shapes, some tapering more or less, others being rounded, and still others being formed with a shoulder and with a bottom cavity of reduced diameter as compared with the remainder of the molding cavity. It will thus be seen that the lower ends of mold charges must be shaped in various ways in order to conform as closely as possible to this considerable variety of shapes at the lower ends of the molding cavities. The present application is concerned with the production of these end-shapes, and their control.

The following is a copy of the entire specification of my original application Serial No. 294,792, and the accompanying drawings are complete reproductions of the drawings of the original application.

This invention relates to the segregation and separation of molten glass into mold charges. It has for its object the production of mold charges of suitable form and homogeneity to be most advantageously used in glass shaping machines, and it comprises a method and apparatus whereby such mold charges may be preformed while segregating them from a supply of molten glass in a furnace or container, and before bringing their external surfaces into contact with relatively cold molds or other supporting or

forming means, and whereby the form and size of such charges may be controlled and varied at will, and without destroying their uniform consistency by the unequal chilling 5 action of external or relatively cold molds or other supports or forming means.

It is a prominent characteristic of molten glass, that when it issues or is withdrawn from the furnace or container, and is exposed to the colder surroundings outside of the furnace, it acquires a partially chilled surface or skin, known in this art as "enamel". This enamel is coldest and stiffest 10 on its outer surface, and gradually merges into the hot and more plastic interior of the glass. When a charge of this glass is delivered to a mold, any undue stretching, rupture, or infolding of the enamel will cause defects in the article being made. Any 15 trapping of air by the glass, due to lapping or folding of the surface of the glass as it is delivered to the molds will also cause defects. To avoid these defects it is desirable to preform the mold change, before it enters 20 the mold, so that its external contour will closely approximate the interior contour of the mold walls, or at least that portion of the mold which receives the gather. This is 25 of special importance in the making of blown 30 glassware. A mold charge which is to form a narrow necked bottle, for example, should be preformed as an elongated cylinder, so that its entire surface may as nearly as possible 35 contact equally with the mold walls for the same length of time. Unequal contact of different portions of the surface, or unequal duration of contact of the different portions tends to produce an unsymmetrically 40 chilled and enameled blank or parison, which will not blow out uniformly, because the hotter portions will stretch more than the cooler portions, resulting in a poor bottle 45 having a wall of uneven thickness.

These conditions have evidently been recognized to some extent by the hand gatherer, practicing his ancient art, who by manipulation of his punty or gathering rod during the gathering operation preformed his gather or mold charge, as well as he could 50 by this primitive method, to fit the mold, or that portion of the mold that receives the gather, thus attempting to avoid undue deformation of the mold charge when deposited in the mold. On the other hand, these 55 conditions have received little or no attention in the gathering or feeding of molten glass as heretofore practiced by machine or other automatic methods.

The present invention accomplishes this 60 preliminary shaping of mold charges with greater ease and exactness than heretofore by the adjustable operation of suitable impelling means coacting with an orifice below which the mold charges are accumulated and suspended, and it employs the elongation of

the suspended charges in controlling their shape. It also makes use of coaction between the impelling means and suitable severing means, convenient adjustments being provided to allow control of the severing 70 means and impelling means as to relative time of operation, speed and position.

Various adjustments of the impelling means as well as of the severing means to control and vary the form of the gathers 75 and mold charges during continuous operation, are herein described as operating adjustments, that is they may be made while the machine is in operation, thus allowing the maintenance of the flow of glass and the 80 uniform heat conditions which are so essential in proper operation of glass feeding apparatus. Stopping of the machine to make adjustments would stop the flow of glass and would have the effect of allowing the 85 glass to chill near the outlet and of changing the heat conditions. As a result the operating conditions would be changed so that the immediate effect of the adjustments could not be observed and employed as a 90 guide in making these adjustments. In the present invention, on the other hand, these adjustments may be made while the apparatus is operating so that the progressive effect of these adjustments may be observed 95 while they are being made, thus giving better control of the operation.

In the accompanying drawings:

Figure 1 is a general front elevation of the apparatus with the lower part or base 100 omitted;

Fig. 2 is a side elevation of the machine, shown partly in section, made approximately along line 2-2 of Fig. 1, with the shear mechanism omitted, and showing the 105 glass furnace and its conduit for the molten glass;

Fig. 3 is a side elevation showing some of the shear mechanism;

Fig. 17 is a bottom view of a section on line 17—17 of Fig. 14;

Figs. 18 and 19 are elevations of the impeller cam partly in section similar to Fig. 15 showing extreme adjustments;

Fig. 20 shows a side elevation of the worm adjustment for the impeller cam;

Figs. 21 and 22 show different shapes of cam lobes for the impeller cam;

Figs. 23, 24, 25 and 26 show sectional elevations of various types of molds with charges of glass in them;

Figs. 27 to 31 inclusive are sectional elevations to illustrate steps in the formation of the mold charge shown in Fig. 23;

Figs. 32 to 36 inclusive are sectional elevations to show steps in the formation of the mold charge shown in Fig. 24;

Figs. 37 and 38 are sections showing steps in the formation of the mold charge shown in Fig. 26;

Figs. 39 and 40 illustrate in section the action of reducing the neck of a suspended gather before severing;

Figs. 41 to 45 inclusive are elevations, partly in section, showing steps in the formation of a more attenuated column of glass issuing as a stream;

Figs. 46 to 49 inclusive show various forms of impellers; and

Figs. 50 and 51 show diagrammatic rear elevations of the right-hand shear cam and roll.

The invention is herein shown embodied in a machine having the necessary mechanical movements and adjustments, and cooperating with a conduit projecting from a glass furnace, from which the molten glass is thus delivered in mold charges to an associated molding or shaping machine.

The molten glass flows from the glass furnace 1 through a channel or conduit 2 (Fig. 2) to an outlet 3. It is there acted upon by an impeller 13 mounted for vertical movement, and provided with various adjustments. As it issues periodically in regular cycles from the outlet, it forms successive gathers from which mold charges are severed by shear blades 4 reciprocating below the outlet. The separated mold charges fall upon a moistened chute 5 and slide upon it to

the molds 6 mounted on the table 7 of the associated shaping machine (Fig. 5).

The channel 2 is made of refractory material surrounded on the bottom and sides by heat insulation 11. At the outer end of the channel is an outlet spout 12, the interior of which is shaped so as to coat with the impeller 13. This spout is held in an iron frame or case 14, which also serves as a retainer for the insulation 11, the spout being surrounded with insulation, except at the outlet 3.

The bed 15 is carried by the same foundation which supports the base of the machine. It serves to support the channel 2 by means of intermediate refractory supports 10 and carries two brackets 16 clamped thereto by screws 17 and which support the spout case 14. The brackets also carry set screws 18 which bear against projections on the spout case and hold the spout against the end of the channel. These screws may be adjusted to allow for expansion and contraction of the channel and spout. The brackets also carry removable drip pans 20 for receiving the cooling water dripping from the shear blade 4 and from the sprays 21.

Over the spout is a cover 22 of refractory material carried in a metal case 23 which also serves as a retainer for heat insulation 11, the metal plate 24 serving to keep the insulation in place. The plate 24 and cover 22 have openings through which the impeller projects. Back of this cover and over the channel is another refractory cover 25 formed so as to retain heat insulation 11 which is covered by a metal plate 26 to keep it in place.

The channel and spout are heated by suitable means, such as a gas burner 27, which projects through the side wall block 30. This burner is provided with air and gas valves 31 for regulating the flame, which partly fills the space over the molten glass. The products of combustion are carried off by the fire brick stack 32 carried on refractory lintels 33, which bridge the channel and are separated at their ends by refractory blocks. At the upper end of the stack is a damper 34 carried on a pivot 35 and adjustable through an arm 36, and connecting rod 37 having a handle at its outer end and provided with notches 38 engaging with a stop 40, thus allowing the damper to be set at any desired opening. By appropriately adjusting the burner and damper the proper temperature may be maintained in and over the channel and spout. The insulation acts to conserve the heat, and the radiation from the rear assists in heating the outlet end, thus tending to maintain a uniform temperature throughout.

A gate 41 for regulating the glass flow is suspended by links 42 from arms 43 fast on the shaft 44 at each end thereof. The

right-hand arm 43 bears a pointer 45 registering with a scale 46 to indicate the setting of the gate. A screw 47 carrying a hand wheel 50 bears against an extension 51 of the right-hand gate arm 43, thus allowing the position of the gate to be adjusted by turning the hand wheel 50. The glass surface in the furnace 1 is preferably maintained at a higher level than that desired in the spout 12 and the level or head desired in the spout may be maintained by adjustment of the gate.

Clamped against the outlet block or spout 12 is an outlet ring 52 (Figs. 6 and 7) made of refractory material. This ring is carried in a metal holder 53 hinged by an open sided bearing 54 to allow ready removal, on a pivot 55 and is drawn up against an abutment by screws 56 (Fig. 5). Between the outlet 20 ring and the spout is a packing 57 of refractory clay. The object of this construction is to allow the size of the outlet to be changed at will by easy and rapid change of the outlet rings. In practice an outlet 25 ring of the size desired is placed in the holder and covered with sufficient plastic clay to form the packing 57. The holder is then hooked over the pivot 55 and drawn up against its abutment, squeezing the plastic packing into place.

The frame of the machine is carried by the base 58 (Figs. 3, 4 and 5) and surrounds the channel and spout. The base carries columns 60 with suitable bearings at their 35 upper ends to carry the drive shaft 61 and pivot shafts. The drive shaft may be driven by a pulley 62 (Fig. 1) as shown and may be connected to a shaping machine by any suitable means for synchronizing its operations with those of this machine. The 40 shaft 61 carries cams 63 for driving the shears and serves as a pivot for the impeller cams.

The shear blades 4 are notched as shown 45 in Fig. 9. This allows them to enclose the glass and to constrict it on all sides as well as to cut it. For this reason they act to separate the glass partly by constriction and partly by cutting, thereby minimizing the 50 shear mark on the severed glass.

The shear blades 4 are fastened to shanks 64 which are carried in adjustable heads or 55 holders 65 (Figs. 8, 9, 10 and 11, which show the right-hand holder), by means of which the blades may be adjusted up, down and sidewise relatively to each other and to the outlet 3, so as to sever the glass at the desired position and to operate to the best advantage. The shank 64 of each 60 blade is removably held in a vertical slide 66 split in its lower portion at 67 (Figs. 10 and 11) and clamped by means of the clamp screws 70. The vertical slide 66 fits a guideway on a cross slide 71 as shown in Fig. 65 10 and may be adjusted up and down by

means of the adjusting screw 72 by its hand wheel 73. The slide 66 may be clamped in place in its guideway by the screw 74 and clamp 75. The cross slide 71, which carries the vertical slide and its adjustment fits in a guideway 78 (Fig. 8), and may be clamped in place by the screw 76 and clamp 77, thus allowing the shear blades to be adjusted for transverse position and clamped to place. The shear blades may be adjusted endwise by moving their shanks in and out in their holders, either for the proper initial setting or for a controlling adjustment, although a preferable operating adjustment is provided for this purpose. In this way the shear blades may be moved in three directions so as to bring them into proper relationship to the outlet and proper alignment with each other. To move the severing plane to a higher or lower level, both shear blades are adjusted up or down as desired, the proper cutting alignment between them being maintained by turning both hand wheels 73 the same amount.

The shear holders above described are carried on the ends of the carriers 80 guided between grooved guide rollers 79 pivoted on the columns 60, and are protected by the guards 81 projecting from these columns. The carriers 80 are moved toward and away from each other by means of levers 82 carrying at their lower ends rollers 83 which engage with slots 84 in the carriers. The shear levers are pivotally mounted on studs 85 and 86 carried on the columns 60. The upper ends of the shear levers are provided with cam rollers 87 which are held by suitable springs 90 against the shear cams 63 which are fixed on the main shaft 61, the cams being shaped to move the shear blades to and from each other to cut off the successive mold charges when formed.

The shears may be stopped in their retracted positions without stopping the rest of the machine by moving the hand lever 91 to the position shown in Figs. 3, 4 and 5. This rocks the shaft 92 and transmits the motion to shaft 93 by means of bevel sector 94 and bevel gear 95. This shaft carries two cams 96 against which bear the rollers 97 carried by the slides 98 so that the rocking of the shaft 93 raises or lowers them. These slides are connected by means of connecting rods 100 with the arms 101 which are pivoted on the studs 85 and 86 with the shear levers 82. These arms bear against the lower side of the shear lever extensions 102. In this way the shear levers may be positively held against the action of the springs 90 to hold the shears inactive in their retracted positions while the cams continue to rotate. By reversing the position of the hand lever 91, the arms 101 will be swung down and the shears will be allowed to resume normal operation. The hand lever 100

91 may be locked in position by means of the latch 103 worked by a knob 104.

- For controlling the shape of the lower ends of the gathers, while the machine is in operation, an operating adjustment is provided for increasing or lessening the rapidity with which the shear blades cut through the glass, by using earlier or later portions of the contour of the shear cams 6 (Figs. 50 and 51). These cams are shaped to give a gradually decreasing speed to the shear slides toward the inner ends of their strokes, so that by varying the point in the path of the slides at which severing begins 10 the severing speed may be varied. For this purpose those portions of the pivot studs 85 and 86 which carry the shear levers 82 are made eccentric to the portions which are supported in the frame, the eccentricity of 15 one pivot stud 86 being set downwardly (Fig. 12) and the eccentric portion of the other pivot stud 85 being set upwardly. This enables these eccentric pivotal supports for the shear levers to be adjusted toward 20 or away from each other. When adjusted toward each other the shear blades meet and sever the glass at an earlier period, at a time when the respective cam rolls 87 are in contact with a steeper or more inclined 25 portion of the cam contour, as shown in Fig. 50, so that the severing operation is performed quicker, and therefore in shorter time, thus making a blunter ended gather. On the other hand, when the eccentric portions 30 of the studs 85 and 86 are turned outwardly, the shear blades meet and sever the glass at a later period in their stroke, at which time their respective cam rolls 87 engage with the less inclined contours of 35 the shear cams 68, as shown in Fig. 51, thus severing the glass in a longer time, and therefore more slowly, and making a more pointed end on the gather. The dot-and-dash tangent lines 105 in Figs. 50 and 51 40 show the relative steepness of the cam contour at the two cutting points. The pivot studs 85 and 86 for the shear levers are turned to utilize their eccentric movements by means of levers 106 (Figs. 1, 12 and 13), 45 which are connected by a rod 107 so as to turn both pivot studs at the same time and to the same extent; but on account of the oppositely arranged eccentricity of the studs, move the pivotal points of the levers in opposite directions. The connecting rod 107 50 may be adjusted for length by a right and left-hand threaded nut 108. One of the levers is provided with a handle 110 for turning the eccentrics. 55 The scale 111 is provided to indicate the extent to which the eccentrics are turned. The scale is read in connection with the pointer 113 attached to the column and may be clamped in any desired position by the 60 screw 112.

The shear blades are cooled between successive severing operations by means of water sprays 21 (Figs. 1 and 6), supplied by pipes 114 and regulated by valves 115. The water from the sprays strikes the blades 70 in their retracted positions and is finally caught by the drain pans 20 from which the water is drained away.

The impeller 13 for timing and controlling the extrusion and formation of the 75 gathers is made of refractory clay and is guided for vertical movement into or through the outlet ring in a line concentric with this ring by the guide shafts 116 and 117 sliding in bearings 120 and 121 respectively which are formed in the spout case (Figs. 2, 6 and 7). The guide shaft 117 carries an arm 122 to which a split holder 123 carrying the impeller is detachably and adjustably secured by clamp screws 124 80 which pass through elongated holes in the holder 123 to allow it to be slid in and out on the arm 122. This arm 122 is clamped to the shaft 117 by a screw 125 allowing it to be swung about the shaft. In this way 85 the impeller holder 123 may be slid radially in and out from the shaft 117 or swung about it and clamped in position to bring the point of the impeller into alignment with the outlet, thus compensating for warping 90 of the impeller or for variation in different impellers. The shaft 117 also carries an arm in which the guide shaft 116 is fastened. The lower end of this shaft comes 95 opposite the scale 127 fastened to the spout case. This scale is graduated to indicate the 100 position of the lower end of the impeller relative to the lower side of the outlet ring. The impeller is clamped in its holder 123 by screws 128, and may be quickly exchanged for another impeller of any desired 105 shape. Various shapes of impellers for different effects are shown in Figs. 45 to 48 inclusive.

The impeller and its carrier are suspended 110 by the connecting rod 130 and its pivots 131 and 132 from the lever 133 pivoted at its hub 134 on the shaft 135. This lever carries an adjusting screw 136 bearing a hand wheel 137. The end of this adjusting screw 115 bears against another lever 138 also pivoted at its hub 140 on the shaft 135, so that both levers are guided side by side between fixed collars. The lever 138 has at its upper end a stud 141 carrying a cam roll 142 which is 120 held against the impeller cam shown in outline at 143 in Fig. 7 by the weight of the impeller and its carrier. The impeller cam thus governs the rise and fall of the impeller. By turning the hand wheel 137 and 125 revolving the adjusting screw 136 the relative angular position of the two levers 133 and 138 may be varied. The effect of this is to raise and lower the working range of the impeller movements. The impeller may 130

also be held inactive in its upper position by turning the latch 144 carried by the lever 133 over the projection 145 carried by the shaft 146.

- 5 In addition to the height adjustment above described, the connecting rod 130 is made adjustable by means of a turn buckle, provided with right and left hand screw threads at its opposite ends, and connecting 10 the upper and lower portions of the connecting rod. Check nuts are provided to clamp the parts tightly after the desired adjustment has been made. By turning the turn buckle, the connecting rod 130 may be 15 lengthened or shortened and the working range of the impeller lowered or raised, as desired. This adjustment may be used in place of, or in addition to the hand wheel adjustment above described.
- 10 The impeller 13 may be held inactive at lower positions projecting into the glass at the outlet, or even through the outlet, by adjusting the connecting rod 130, which connects the impeller 13 with the lever 133 and 25 operating the latch 144. By thus holding the impeller inactive at its lower positions and adjacent the outlet, the gravity outflow of the glass can be timed and shaped for various forms of gathers by operating the 30 severing means only.

The length of stroke of the impeller may be varied by sliding the pivot 131 of the connecting rod 130 in the slot 147 provided in the lever 133. This changes the effective 35 length of the lever. This pivot 131 is provided with a nut by means of which it may be clamped in any desired position as indicated by graduations along the slot 147 to give the impeller the desired length of stroke.

The impeller cam is composed of several parts as shown in Figs. 15 to 19 inclusive. The sleeves 150 and 151 are loose on the main drive shaft 61 and are provided with bevel gears 152 and 153 respectively at their outer ends, and with flanges 154 and 155 at their inner ends. These flanges form part of the cam surface and also hold removable cam lobes 156 and 157 which serve to govern the rise and fall of the impeller respectively. The lobe 156 which raises the impeller, is carried by the right-hand flange 155 and is removably secured to it by clamp screws 158 which enter the slots 160 therein and serve to locate the lobe. The left-hand flange 154 carries the lobe 157 which governs the fall of the impeller. This lobe is also detachably secured to the flange 154 by means of clamp screws 161 which enter the slots 162 therein and thus locate the lobe. By this arrangement the two cam lobes can be revolved about the shaft independently of each other so that their angular position relative to each other and around shaft may be varied within certain limits. For in-

stance Figs. 14 to 17 inclusive show the lobes set $17\frac{1}{2}$ degrees apart, while Fig. 18 shows them set close together. Fig. 19 shows them separated to a maximum of 40 degrees, a pin 159 being provided to prevent separating 70 them beyond the allowable limits.

The main drive shaft 61 revolves in the direction of the arrow shown on the drive pulley 62 (Fig. 1) and drives the bevel gears 163 and 164 which are fastened to 75 it. These bevel gears drive the pinions 165 and 166 which in turn drive the bevel gears 152 and 153 thus rotating the sleeves 150 and 151 with their cam parts, respectively. The pinions are mounted for rotation on 80 holders 167 (Fig. 20) which are revolubly mounted on the main shaft 61 and provided with worm wheel sectors 170. These sectors are engaged by worms 171 (Fig. 20) carried on shafts 172 which are provided with hand wheels 173 and 174 respectively. By revolving the hand wheels the pinion holders 167 are rotated about the shaft 61 thus moving the sleeves 150 and 151 relative to the driving gears 163 and 164, respectively. 85 This has the effect of angularly advancing or retarding the sleeves 150 and 151 bearing the cam lobes 156 and 157. In this manner the lobes may be set to act at any desired time relative to the shears and to each other.

By turning the right-hand hand wheel 174 the right-hand sleeve 151 is advanced or retarded, thus advancing or retarding the cam lobe 156 by which the impeller is raised. By turning the left-hand hand wheel 173 the cam lobe 157, which governs the fall of the impeller is advanced or retarded. By properly turning both hand wheels the same amount both lobes as a whole may be advanced or retarded, correspondingly changing the time of the impeller operations relative to the time of the shear operations. In this manner the various characteristics of the impeller action may be varied, and its operating period may be advanced or retarded relative to the severing operation. 100 For visibly indicating these adjustments of the impeller cams, the shafts 172 are provided with gear teeth meshing with teeth on the indicator dials 175 which register with the pointers 180.

One effect of advancing or retarding the cam lobe 156 by which the impeller is raised, is to make the up-stroke of the impeller earlier or later relative to the severing operation. The rapidity of the rising movement of the impeller during the severing operation may thus be varied by taking advantage of the contour of the cam lobe 156 which is preferably shaped to give a gradually increasing speed to the impeller during the first part of its up-stroke. By advancing the cam lobe 156 relatively to the shear cams the impeller may be made to rise more rapidly during severing and by re- 110 115 120 125 130

tarding this lobe the impeller may be made to rise more slowly during severing. This cam lobe may also be set so that the impeller begins to rise after the severing is 5 partially or entirely completed.

The characteristics of the impeller stroke may be still further altered by substituting other cam lobes which provide a rise or fall of any desired character. The cam 10 lobes 176 and 177 shown in Fig. 21, for instance, give a rise and fall extending over a longer period than those in Fig. 15. The lobes 178 and 179 shown in Fig. 22 give a quicker rise and fall than those shown 15 in Fig. 15. These lobes are arranged so as to be readily changed by simply loosening the clamp screws which are carried by the lobes, and substituting other lobes.

The chute 5 is formed of porous material 20 such as carbon and is placed in a sloping position as shown in Fig. 2 with its upper end under the outlet 3 to receive the separated mold charges, and with its lower end over the mold charging station of the shaping machine as shown in plan in Fig. 5. The chute is supplied with water through 25 a flexible tube 181 which connects with a recess 182 (Fig. 6) formed in the upper end of the chute. A valve 183 regulates the 30 water supply. Sufficient water is supplied to moisten the chute. When the glass falls on the chute the water is turned to steam where the glass touches it, so that the glass slides freely and rapidly down the chute 35 on a film of steam and drops into the mold 6. The chute is supported on vertical pivots so mounted that it may be swung out of or into the glass receiving position to interrupt 40 or begin the delivery of the mold charges to the molds as desired. When the chute is swung out, the glass drops through an opening in the base 58 into a suitable receptacle.

In operation, the gate 41 is raised to the 45 proper point to maintain the desired head of glass over the outlet and the machine is set in motion, reciprocating the impeller and the shears. The molten glass issues from the outlet under the combined influence 50 of gravity and the action of the impeller, which times and controls its accumulation in gathers which are successively suspended from the outlet ring and from the impeller end. For each complete reciprocation of the 55 impeller there is a reciprocation of the shears which severs a mold charge from each suspended gather. After each severing operation the freshly cut end or stub remaining below the outlet, and forming the lower end 60 of the succeeding gather, is moved upwardly, or its downward movement is retarded, by the action of the impeller.

By using appropriate sizes of outlet ring and impeller, and by proper setting of the 65 various adjustments, the shape of the top,

body, and lower end of the mold charge may be varied separately at will as herein-after described.

The size of the outlet ring is chosen with relation to the general shape of the body of 70 the mold charge, a smaller diameter outlet being used for a long mold charge than for a short charge. For a nearly spherical charge a larger diameter outlet is used than for a longer cylindrical charge. The relation of the diameter of the gather to the outlet size depends partly on the speed of the 75 machine and the viscosity of the glass, as these influence the elongation and consequent reduction in diameter of the glass 80 column issuing from the outlet. In general a higher speed requires a larger outlet than a slower speed does, while greater viscosity requires a larger outlet than a lower viscosity would. 85

The size of the impeller end depends to a certain extent on the size of the outlet used, since the impeller and outlet coact to produce effects herein-after described. The larger the outlet, the blunter the end of the 90 impeller may be, other conditions being equal. The size of the impeller end also depends on the general shape of the mold charge desired. For a short compact charge a blunter ended impeller is preferably used, 95 while for a more elongated charge a more pointed impeller is preferred.

The weight or quantity of the mold charge 100 may be regulated by the gate, which determines the depth of glass over the outlet. Raising the gate gives a heavier charge and lowering it decreases the weight of the charge.

The impeller acts upon the glass partly by displacement and partly by adhesion of the 105 glass to it. Consequently as the impeller moves downward it gives a downward or extrusion impulse to the glass issuing from the outlet. This extrusion impulse aids the gravity head at the outlet and increases the 110 rate of discharge of the glass. As the impeller moves upward it gives an upward or intrusion impulse to the glass within and below the outlet. This intrusion impulse opposes the gravity head at the outlet, tending to retard the discharge of glass from the outlet, and may be made to reverse the motion of the glass within and below the outlet, raising it up to an extent depending on the extent and strength of the impulse. The impeller also furnishes part of the support for 115 the glass below the outlet, this support being greatest when the impeller protrudes below the outlet and less for higher positions of the impeller. As the impeller rises it gradually withdraws this support, transferring more of the weight of the suspended glass to the outlet. Another effect of projecting the impeller below the outlet is to enlarge 120 the neck of the suspended gather by the dis- 125

placement. This also increases the amount of support.

The downward or extrusion impulse of the impeller may be used to control the shape of the body and upper end of the gather and its resulting mold charge. This impulse tends to increase the diameter of the suspended and elongating glass, in proportion to the extent and strength of the impulse. By adjusting the hand wheel 173 to advance the cam lobe 157 the extrusion impulse comes earlier which tends to increase the diameter of the body of the gather rather than the diameter of the upper end only. By retarding the impulse it tends to enlarge only the upper end of the gather. Increasing the extent of the downward impulse, which may be done by lengthening the impeller stroke, tends to enlarge more of the gather, as for instance both the body and the upper end. The strength of the impulse may be varied by varying the working position and size of the impeller and by varying the character of its downward stroke. A lower position tends to give a stronger impulse and vice versa. A larger or blunter impeller also gives a stronger impulse. By changing the cam lobe 157 the character and duration of the downward stroke and therefore of the extrusion impulse may be varied. A faster downward stroke of shorter duration increases the strength of the impulse but applies it locally to a more limited portion of the gather. The decrease in diameter of the gather due to its elongation by gravity may thus be compensated for to any extent. By shaping the cam lobe so as to increase or decrease the relative speeds of the downward stroke at different parts of this stroke a variety of effects may be secured, allowing more varied control of the shape of the gather. In this manner by use of the proper parts and by proper setting of the various adjustments the shape of the body and upper end of the gather and its resulting mold charge may be varied.

By turning the hand wheel 174 and setting the cam lobe 156 to raise or reverse the glass adjacent to the outlet while the shears are severing, the upward or intrusion impulse of the impeller, coacting with the constricting and severing action of the shears may be used to vary the shape of the lower end of the gather and its resultant mold charge. The contour of the cut glass surface may be varied by varying the cutting speed of the shears as previously described so that the shape of the stub and therefore of the end of the succeeding mold charge may be controlled. By having the shears cut as quickly as possible during the raising of the stub, a blunt ended stub is obtained. By having them cut more slowly, as the glass forming the stub is raised by the intrusion impulse, a more pointed stub is obtained. The raising speed of the glass may also be varied by advancing or retarding the intrusion impulse and taking advantage of the gradual increase in upward speed of the impeller during its stroke due to the shape of the cam lobe 156. This is similar to the described manner of varying the shear speed during severing. By setting the cam lobe 156 so that the impeller does not rise until after the shear blades have entered the glass a shoulder may be formed at the lower end of the gather. (Figs. 37, 38.) This shoulder may be made more or less abrupt by adjustment. In this manner various combinations of raising and cutting speeds may be obtained, allowing the shape of the lower end of the mold charge to be varied.

The up-stroke of the impeller and its resulting intrusion impulse may also be used to vary the shape of the gather above the part formed by the severing operation. The initial formation of the stub by cooperation between the intrusion impulse and the shears has already been described. The further elongation, due to its weight, of the stub and of the portion of the gather above the stub may be varied or its effect may be compensated for by varying the character of that part of the up-stroke taking place after severing. For instance, by retarding the discharge of the glass the lower part of the gather may be allowed to elongate before the remainder of the gather is allowed to form. This elongation decreases the diameter of the elongated part. By diminishing the retardation and allowing a greater discharge of the glass, the lower part of the gather may be increased in diameter. Increasing the length of the impeller stroke increases the extent of the intrusion impulse. The strength of this impulse may also be increased by lowering the working position of the impeller. The character and duration of the stroke may also be varied by changing the cam lobe 156. A faster up-stroke increases the strength of the intrusion impulse but applies it to a more limited portion of the gather by shortening its duration. By forming the cam lobe to change the relative speeds at different portions of the up-stroke, various effects may be secured. For instance, the first part of the up-stroke may be made fast enough to secure the proper shape of stub while the remainder of the stroke may be made to give any desired retardation to the glass. Thus the impeller might be held stationary for a certain period, before completing the remainder of the up-stroke. This gives a varied control over the shape of the gather, and especially over the shape of its lower portion.

One effect of raising the glass below the outlet during and immediately after the severing operation is to keep it out of contact

with all parts of the shear blades except the immediate cutting edges. This minimizes the chilling of the glass from the relatively colder shear blades and also aids in keeping the blades cooler. It is therefore preferable to operate this device with such adjustments as will allow the cut surface of the glass to be raised clear of the shear blades during and after severing.

10 By raising or lowering the shears they may be made to sever the glass at a higher or lower level, leaving a shorter or longer stub respectively. This length of stub has an influence on the length of the gather. A 15 longer stub tends to elongate the gather and a shorter stub tends to produce a shorter gather. This influence extends to the lower part of the gather especially.

By properly combining all the variable

20 adjustments and allowing for or making use of the elongation and decrease of diameter of the gather during its accumulation and suspension, the shape of the gather and its resulting mold charge may be varied to 25 suit various types of molds to which the mold charge is to be delivered. Some examples of this variation are shown in Figs. 23 to 26 which represent various molds containing mold charges which have just been 30 delivered to them. Fig. 23 for instance, shows a blank-mold for a narrow neck bottle with a gradually sloping shoulder. It is a mold of the type in which the blank is formed in an inverted position, the 35 formed blank being reverted for blowing to final form. The mold charge for this mold is largest at the upper end, tapering down gradually toward the lower end, being nearly a frustum of a cone. This 40 charge fits the mold closely, tending to form a good blank when the forming pressure is applied. Fig. 24 shows a press mold in which a tumbler is to be pressed. The mold charge for this mold is made chunky 45 and compact, so as to settle down and fill the lower end of the mold as soon as possible after delivery. This allows the pressing plunger to act on the glass to the best advantage. Fig. 25 shows a blank mold for 50 a wide mouth bottle of cylindrical form. The mold charge for this is made as nearly cylindrical as possible so that it fits the mold closely and quickly fills out the lower portion of the mold when the forming pressure is applied. Fig. 26 shows a blank 55 mold for a narrow neck bottle having an abrupt shoulder below the neck. The mold charge for this differs from the mold charge shown in Fig. 25 by having an elongation or point 190 formed at its lower end 60 to fit the neck portion of the mold.

The steps in the formation of the mold charge required for the mold of Fig. 23 are shown in Figs. 27 to 31 inclusive. A 65 portion of the outlet block or spout is shown

in section, with the outlet ring 52 below it. A medium sized impeller shaped at the end like Fig. 48 is shown. The shear blades 4 are shown diagrammatically and the arrows beneath them indicate the direction 70 of their motion. The cutting speed of the shears and the raising speed of the glass below the outlet are set so as to shape the stub to give the desired shape to the end of the gather in connection with the elongation later given it. The shape of the cut resulting from this setting is shown in Fig. 31 where the shears have just completed severing. The shape of this cut is the result of the motion of the shears combined with 80 the upward motion of the glass imparted by the impeller moving upward during the cut. In Fig. 27 the stub is rounded out at the point 191 and is beginning to elongate. At the same time the entire stub has been 85 raised into the outlet by the upward motion of the impeller which is still moving upward to retard the glass. In Fig. 28 the impeller has reached its upper position and pauses there while the glass is discharging from 90 the outlet to form the body of the gather. When the glass has assumed the shape shown in Fig. 28 the impeller starts to move downward, accelerating the discharge of 95 glass through the outlet as it approaches its low position shown in Fig. 29. Here the upper end of the gather is shown swelled out by the accelerated discharge of the glass. The impeller remains in this low position for a definite time while the gather elongates. It then starts to rise and has risen to the point shown in Fig. 30, when the shear blades make contact with the glass. The severing then commences and takes 100 place during the interval between Fig. 30 and Fig. 31 while the upward motion of the impeller raises the glass to form the point 192 of the stub by cooperation with 105 the shears.

The steps in the formation of the mold 110 charge shown in Fig. 24 are shown in Figs. 32 to 36 inclusive. The impeller for the compact charge desired is made blunter than in the previous example, being like that shown in Fig. 49. The outlet ring 52 is 115 also made of a larger diameter, to give the necessary increased diameter of gather. The shears are set to sever more quickly so as to produce a stub which is blunt when rounded out, as shown in Fig. 32 where 120 the impeller is moving upward. In Fig. 33 the impeller has reached its upper position and the body of the gather is discharging through the outlet. The impeller then starts to move downward and is shown still 125 moving downward in Fig. 34, having, by its downward impulse, swelled the gather as shown. This swelling action is continued by the continued downward motion of the impeller until the shears contact with the 130

glass as shown in Fig. 35. The impeller cam is set so that the impeller starts up immediately after reaching the position shown in Fig. 35. The severing operation 5 takes place between the positions shown in Figs. 35 and 36. The effect of the impeller cam adjustment, both for character of the stroke and for relative time, is to continue 10 swelling the gather until the severing operation starts and then to allow a minimum time for elongation of the gather before or during severing so that a short compact spheroidal gather is produced.

Figs. 37 and 38 illustrate the modifications 15 employed to obtain the mold charges shown in Fig. 26. Here a more pointed impeller is used, the one shown in Fig. 46 being employed. The orifice ring is chosen of the proper size to form the body of the gather. 20 The shears are set lower down than in the first example, namely Figs. 27 to 31, to form a longer stub. They are also set for slower cutting speed than in this first example and the impeller is set to rise later to give the 25 shapes of shoulder and point shown. The impeller stroke is set so as to allow the proper elongation of this point and after this to give a cylindrical body to the gather by the proper amount of additional impulse 30 to the glass.

The mold charge shown in Fig. 25 is like the body of the charge shown in Fig. 26, the point 190 of Fig. 26 being absent. To form this charge the shears are set to cut 35 more rapidly than for the charge of Fig. 26. The impeller is also set to give slower rise to the glass during severing. This gives the blunter point shown.

Figs. 39 and 40 illustrate a setting of the 40 impeller stroke by which the impeller moves upward rapidly enough, before the severing operation starts, to form a reduced neck 193 above the gather before it is severed. This gives an approximately pear shaped gather. 45 It also avoids the severing of a large column of glass.

Figs. 41 to 45 inclusive illustrate the 50 delivery of mold charges at such speed and temperature that the glass issues from the outlet in a more elongated column breaking into a stream between interruptions. Here the impeller is moving upwardly in Figs. 44, 45 and 41, having reached its upper position in Fig. 42. It then moves downward to 55 accelerate the flow of glass and reaches the lower position in Fig. 43 after which it begins to move upward again. The effect is to withdraw or retract the stub of glass and interrupt the downward flow as shown. It 60 also tends to compact and round the end of the stream and to make the mold charge as compact as possible under the circumstances. It thus aids in minimizing the difficulties due to lapping and folding of the charge when 65 it settles in the mold.

One of the advantages of the illustrated embodiment of the invention over that type of glass feeding machine which employs a relatively large impeller or plunger, is in the more uniform heat distribution in the 70 mold charge. This desirable result is obtained by the use of an impeller of comparatively small diameter which greatly reduces the screen or shadow effect of a larger impeller, which cuts off the direct radiation of 75 heat from the furnace in the rear to the front of the forehearth, and thereby produces a chilled zone on the front of the mold charge. By the use of a small impeller as described, this chilling of the glass is reduced to a minimum and to all practical purposes entirely removed.

The organized machine shown and described herein as a preferred embodiment of this invention is only one of many possible 85 embodiments of the invention. It should be understood that the various features of the invention may be modified, both in structure, combination, and arrangement, to adapt the invention to different uses or different 90 conditions of service.

In order to provide a full and clear understanding of the invention herein claimed I have reproduced herein the complete specification and drawings of the original application Serial No. 294,792 of which the present application is a division. That specification and those drawings disclose many novel apparatus and process features that are patentably separate from the invention claimed herein. The claims of this application are directed solely to that inventive matter, contained in the original application, characterized by the cutting of the glass while glass is being moved upward past the severing 100 plane. Apparatus and processes disclosed in said original application, and not limited to said upward movement during cutting, are claimed in said original application and in other divisions thereof.

I claim as my invention:

1. In the manufacture of glassware, the method of delivering to successively presented molds, continuous series of similar charges of molten glass of shape and weight 115 appropriate to the particular molds to be fed, which method comprises discharging molten glass, of proper viscosity, through a delivery orifice of a proper contour and area to permit the feeding of charges appropriate to the molds to be fed, severing a mold charge from the discharged glass, by thrusting shear blades through the discharged glass at a level spaced below said delivery orifice, raising a portion of the 120 glass past the severing plane while the shear blades are cutting through the glass, thereby imparting a rounded or conoidal shape to the stub of glass remaining above the severing plane after severance, and initiat- 130

ing through said delivery orifice, for the next succeeding mold charge, a new discharge of glass having at its lower end a rounded or conoidal shape resulting from 6 the interaction between the shear blades and the glass during the preceding cutting operation.

2. The method of feeding molten glass from a parent body in a succession of similar mold charges having rounded or conoidal lower ends, that comprises periodically flowing glass downwardly from the parent body through a submerged outlet, the glass being in a condition suitable for working 15 and such that a compact mass of glass at least equal to a mold charge is accumulated by suspension of the issuing glass beyond the outlet, shearing a mold charge from each pendant mass by the simultaneous action of four shearing edges which together 20 embrace and constrict the glass concentrically around the axis of the outlet, retracting said shearing edges upon the completion of the severing operation and, during 25 the severing operation, lifting past the severing plane a portion of the discharged glass, thereby imparting a rounded or conoidal shape to the stub of glass remaining above the shears after the severing operation, and initiating through said delivery 30 orifice a new discharge of glass having at its lower end a rounded or conoidal shape resulting from the interaction between the shear blades and the glass during the preceding severing operation.

3. In the manufacture of glassware, the method of delivering to successively presented molds, continuous series of similar charges of molten glass of shape and weight 40 appropriate to the particular molds to be fed, which method comprises discharging molten glass, of proper viscosity, through a delivery orifice of a proper contour and area to permit the feeding of charges appropriate to the molds to be fed, severing a mold charge from the discharged glass, by thrusting shear blades through the discharged glass at a level spaced below said delivery orifice, causing the speed of movement 45 of the shear blades to decrease during an appreciable time while the shear blades are cutting through the glass, raising a portion of the glass past the severing plane while the shear blades are cutting 50 through the glass, thereby imparting a rounded or conoidal shape to the stub of glass remaining above the severing plane after severance, and initiating through said delivery orifice, for the next succeeding mold charge, a new discharge of glass having at its lower end a rounded or conoidal shape resulting from the interaction between the shear blades and the glass during 55 the preceding cutting operation.

4. In the manufacture of glassware, the

method of delivering to successively presented molds, continuous series of similar charges of molten glass of shape and weight appropriate to the particular molds to be fed, which method comprises discharging molten glass, of proper viscosity, through a delivery orifice of a proper contour and area to permit the feeding of charges appropriate to the molds to be fed, severing a mold charge from the discharged glass, by 70 thrusting shear blades through the discharged glass at decreasing speed and at a level spaced below said delivery orifice, raising a portion of the glass past the severing plane while the shear blades are cutting 75 through the glass, thereby imparting a rounded or conoidal shape to the stub of glass remaining above the severing plane after severance, and initiating through said delivery orifice, for the next succeeding 80 mold charge, a new discharge of glass having at its lower end a rounded or conoidal shape resulting from the interaction between the shear blades and the glass during 85 the preceding cutting operation.

5. In the art of feeding molten glass in a succession of mold charges periodically cut off by means of coacting shear blades from glass delivered downwardly through a discharge outlet, the steps of raising a portion 90 of the glass past the said shear blades while the shear blades are cutting through the glass, and causing the speed of movement of the shear blades to decrease during an appreciable period while the shear blades are 95 cutting through the glass, the lifting of the glass and the decreasing speed of the shears coacting to impart a conoidal shape to the stub of glass remaining above the shears after the severing operation.

6. In the manufacture of glassware, the method of delivering to successively presented molds, continuous series of similar charges of molten glass of shape and weight appropriate to the particular molds to be fed, which method comprises discharging molten glass, of proper viscosity, through a delivery orifice of a proper contour and area to permit the feeding of charges appropriate to the molds to be fed, severing a mold charge 110 from the discharged glass, by thrusting shear blades through the discharged glass at a level spaced below said delivery orifice, raising a portion of the glass past the severing plane while the shear blades are cutting 115 through the glass, thereby imparting a rounded or conoidal shape to the stub of glass remaining above the severing plane after severance, initiating through said delivery orifice, for the next succeeding mold 120 charge, a new discharge of glass having at its lower end a rounded or conoidal shape resulting from the interaction between the shear blades and the glass during the preceding cutting operation, and producing mold 125 charge, a new discharge of glass having at its lower end a rounded or conoidal shape resulting from the interaction between the shear blades and the glass during the preceding cutting operation, and producing mold 130

charges having differently shaped conoidal lower ends by changing the speed at which the glass is raised past the severing plane.

7. In the manufacture of glassware, 5 the method of delivering to successively presented molds, continuous series of similar charges of molten glass of shape and weight appropriate to the particular molds to be fed, which method comprises discharging 10 molten glass, of proper viscosity, through a delivery orifice of a proper contour and area to permit the feeding of charges appropriate to the molds to be fed, severing a mold charge from the discharged glass, by thrusting shear blades through the discharged glass at a level spaced below said delivery orifice, causing the speed of movement of the shear blades to decrease during an appreciable period while the shear blades are 15 cutting through the glass, raising a portion of the glass past the severing plane while the shear blades are cutting through the glass, thereby imparting a rounded or conoidal shape to the stub of glass remaining 20 above the severing plane after severance, initiating through said delivery orifice, for the next succeeding mold charge, a new discharge of glass having at its lower end a rounded or conoidal shape resulting from 25 the interaction between the shear blades and the glass during the preceding cutting operation, and producing mold charges having differently shaped conoidal lower ends by 30 changing the rate at which the speed of the shear blades so decreases.

8. The method of giving a rounded or conoidal form to the lower ends of mold charges of molten glass which are discharged in succession from a supply through an orifice, which method comprises periodically discharging a mass of molten glass from the orifice, exerting upon each mass after it is discharged, an upward retractive pull sufficient to raise a portion of the glass past 45 a severing plane thereby lifting a portion of the discharged glass past the severing plane, thrusting shear blades toward the center of the upwardly moving glass thereby producing a localized rounded or conoidal shape on that portion of the mass which is above the shear blades after the severing operation, and initiating through said orifice for the next succeeding mold charge a new discharge of glass having at 50 its lower end a rounded or conoidal shape resulting from the interaction between the shear blades and the glass during the preceding cutting operation.

9. The method which comprises causing 60 molten glass to issue from an outlet, severing the glass by opposed shear members spaced below and meeting in axial alignment with the outlet, and moving the mass of glass adjacent to the shears upwardly during the severing operation.

10. The method of shaping the lower ends of a succession of mold charges of molten glass delivered downwardly through an outlet from a container, which comprises periodically causing glass below said outlet 70 to move upwardly, and severing the glass by oppositely directed shear blades passing through the upwardly moving glass at a level spaced below the outlet.

11. The method of forming a succession 75 of mold charges of molten glass that comprises producing, at the outlet of a glass container, a succession of freely-hanging masses of glass, and cutting off a mold charge from each of said suspended masses 80 by a pair of cooperating shear members meeting in axial alignment with and spaced below the outlet, while lifting the glass relative to the cutting means, and thereby producing a conoidal lower end upon the next 85 succeeding mass.

12. The method of shaping the lower ends of a succession of mold charges of molten glass delivered downwardly through an outlet from a container, which comprises periodically causing glass below and adjacent to said outlet to move upwardly, thrusting oppositely directed shear blades through the upwardly moving glass and immediately withdrawing the blades, whereby the shape 90 imparted to the glass remaining above said shear blades, after the severing operation, is retained as the shape of the lower end of the next succeeding mold charge.

13. The method of shaping the lower ends 100 of a succession of mold charges of molten glass delivered downwardly through an outlet from a container, which comprises periodically causing glass below said outlet to move upwardly, severing the glass by oppositely directed shear blades passing through the upwardly moving glass at a level spaced below the outlet, at such speed as to produce a conoidal stub above said shear blades, and quickly withdrawing the 105 shear blades, thereby preserving at the lower end of the next succeeding mold charge the shape imparted to the glass remaining above said shear blades after the severing operation.

14. The method of producing and shaping a mold charge of molten glass that comprises causing molten glass to issue from a container in a pendant column, severing said column by a pair of shears having their 110 cutting edges meeting in axial alignment with and spaced below the container, and lifting the glass adjacent to the point of severance during at least a portion of the severing operation.

15. The method of producing and shaping a mold charge of molten glass that comprises delivering molten glass from a container in a pendant column, causing a portion of said column to move upwardly with 115

- a predetermined movement and severing the column by cooperating shear blades meeting at the center of the upwardly moving portion of said column.
5. 16. The method of producing and shaping a mold charge of molten glass, that comprises delivering molten glass from a container in a pendant column, causing an upper portion of said column to move upwardly with a predetermined movement, and severing the column by cooperating shear blades meeting at the center of the upwardly moving portion of said column.
10. 17. The method of producing and shaping a mold charge of molten glass, that comprises delivering molten glass from a container in a pendant column, causing a portion of said column to move upwardly with a predetermined movement, and severing the column by cooperating shear blades operating in a generally horizontal direction through the upwardly moving portion of said column, said shear blades having a predetermined movement whereby a desired 25 shape is imparted to the portion of the glass remaining above the shear blades after the column is severed.
15. 18. The method that comprises causing molten glass to issue from a container in a succession of pendant columns, causing a portion of each of said columns to move upwardly with a predetermined movement, severing the column by passing oppositely directed overlapping shear blades through the upwardly moving portion of each column, the upward movement and the speed of the shears being coordinated to impart a conoidal shape to the glass remaining above the shears after severing.
20. 19. The method of producing and shaping a mold charge of molten glass, that comprises causing molten glass to issue from a container in a pendant column, severing said column by means of cooperating shear blades meeting at the center of the column, and lifting glass relative to the said shear blades prior to and during severance.
25. 20. The method of producing and shaping a mold charge of molten glass that comprises causing molten glass to issue from a container in a succession of pendant columns, severing each column by means of overlapping shear blades meeting at the axis of said column, and lifting the glass relative to the said shear blades prior to and during severance and by a predetermined movement, whereby a desired characteristic shape is imparted to the severed portions above and below the shears.
30. 21. The method of producing and shaping a mold charge of molten glass, that comprises causing molten glass to issue from a container in a pendant column, severing said column by means of shear blades having a predetermined cutting movement and lifting glass relative to the said shear blades prior to, during, and after severance, and by a predetermined movement.
35. 22. The method of producing and shaping a mold charge of molten glass, that comprises causing molten glass to issue from a container in a pendant column, severing said column by means of shear blades having a predetermined cutting movement, and lifting glass relative to the said shear blades during and after severance and by a predetermined movement.
40. 23. The method of segregating a mass of molten glass from a source of supply, which comprises flowing the glass down and around the end of an impeller, accumulating a desired suspended mass of the glass below and around the impeller, arresting and reversing said flow of glass by upward movement of said impeller, and severing the glass by cooperating shear blades passing through the upwardly moving glass.
45. 24. The method of segregating and separating a mass of molten glass from a source of supply, which comprises flowing the glass through an orifice downwardly around the end of an impeller, accumulating the flow of glass in a depending mass below the impeller, arresting further accumulation and reversing the flow of the glass through the orifice by upward movement of the impeller, and cutting off the accumulation by means of shear blades meeting at the central portion of the flowing glass while the glass is moving upwardly.
50. 25. The method of forming molten glass into a mold charge, which comprises discharging a gather of the glass through an outlet, suspending the gather from the outlet and from coating supporting means, elongating the gather, arresting and reversing the flow of the glass by upward movement of said coating supporting means, and severing a mold charge from the said gather by thrusting shear blades through the glass while the glass is moving upwardly.
55. 26. The method of obtaining mold charges of molten glass, which comprises discharging glass through an outlet, suspending it in successive gathers from the outlet and from coating impelling means, retarding the further discharge of glass by upward movement of said impelling means, and severing mold charges from the said gathers by thrusting shear blades through the glass at a level spaced below the outlet while the glass is moving upwardly.
60. 27. The method of forming a gather of molten glass, which comprises discharging glass through an outlet, suspending the glass in a gather beneath said outlet, thrusting a member into the interior of the suspended gather and thereby expanding the glass below said outlet, severing a mold charge from said gather by thrusting shear blades

through the glass, and moving the glass upwardly relative to the said shear blades during at least a portion of the severing operation.

28. The method of separating a mold charge of molten glass from a supply of the glass, which comprises flowing the glass downwardly around the end of an impeller and through an outlet, accumulating the discharged glass in a depending mass below the outlet, arresting and reversing the movement of the glass below said outlet by upward movement of said impeller, and severing a mold charge from the depending mass by thrusting shear blades through the upwardly moving portion of said glass.

29. The method of feeding mold charges from a supply of molten glass, which comprises maintaining substantially constant gaseous pressure on the upper surface of the supply, then discharging the glass from an outlet submerged by said supply, accelerating the discharge by downward movement of an implement in adhesive contact with the glass, suspending the discharged glass in a gather beneath said outlet, then moving the said implement upwardly, and thereby arresting and reversing the movement of the glass below said outlet, shearing a mold charge from the suspended gather by cooperating shear blades meeting at the central portion of the upwardly moving glass and spaced below the outlet, and repeating the said operation in regular cycles.

30. The method of feeding a supply of molten glass in mold charges, which comprises maintaining substantially constant gaseous pressure on the upper surface of said supply, discharging the glass through an outlet submerged by said supply, then accelerating the discharge by downward movement of an implement in adhesive contact with the glass, suspending the discharged glass in a gather beneath the outlet, shearing a mold charge from the sus-

pended gather at a level spaced below outlet past the shearing level, lifting the glass below said outlet, by upward movement of said implement, during at least a portion of the severing operation, and repeating the said operations in regular cycles.

31. The method of feeding mold charges from a supply of molten glass, which comprises maintaining a substantially constant gaseous pressure on the upper surface of said supply, discharging the glass from an outlet submerged by said supply, periodically retarding the discharge and reversing the movement of glass below said outlet by periodic upward movement of an implement in adhesive contact with the glass, to form successive suspended gathers of the glass beneath the outlet, periodically accelerating the discharge by the periodic alternate downward movements of said implement to compensate for the attenuation of the upper portion of each suspended gather, and shearing a mold charge from each suspended gather after acceleration and during the retarding and reversing operation by means of shear blades spaced below the outlet and meeting in axial alignment therewith.

32. The method of producing and shaping mold charges of molten glass, which comprises periodically discharging molten glass downwardly through an outlet and past a severing plane spaced below the outlet, severing the glass by thrusting shear blades through the glass at a speed which decreases during the severing operation, lifting the glass adjacent to the severing plane during the severing operation, thereby imparting a conoidal shape to the stub of glass remaining above the severing plane after severance, and initiating a new discharge of glass having at its lower end the said conoidal-shaped stub.

KARL E. PEILER

through the glass, and moving the glass upwardly relative to the said shear blades during at least a portion of the severing operation.

5 28. The method of separating a mold charge of molten glass from a supply of the glass, which comprises flowing the glass downwardly around the end of an impeller and through an outlet, accumulating the discharged glass in a depending mass below the outlet, arresting and reversing the movement of the glass below said outlet by upward movement of said impeller, and severing a mold charge from the depending mass by 10 thrusting shear blades through the upwardly moving portion of said glass.

29. The method of feeding mold charges from a supply of molten glass, which comprises maintaining substantially constant 20 gaseous pressure on the upper surface of the supply, then discharging the glass from an outlet submerged by said supply, accelerating the discharge by downward movement 25 of an implement in adhesive contact with the glass, suspending the discharged glass in a gather beneath said outlet, then moving the said implement upwardly, and thereby arresting and reversing the movement of the glass below said outlet, shearing a mold 30 charge from the suspended gather by cooperating shear blades meeting at the central portion of the upwardly moving glass and spaced below the outlet, and repeating the said operation in regular cycles.

35 30. The method of feeding a supply of molten glass in mold charges, which comprises maintaining substantially constant gaseous pressure on the upper surface of said supply, discharging the glass through 40 an outlet submerged by said supply, then accelerating the discharge by downward movement of an implement in adhesive contact with the glass, suspending the discharged glass in a gather beneath the outlet, and repeating the 45 let, shearing a mold charge from the sus-

pended gather at a level spaced below outlet past the shearing level, lifting the glass below said outlet, by upward movement of said implement, during at least a portion of the severing operation, and repeating the 50 said operations in regular cycles.

31. The method of feeding mold charges from a supply of molten glass, which comprises maintaining a substantially constant gaseous pressure on the upper surface of 55 said supply, discharging the glass from an outlet submerged by said supply, periodically retarding the discharge and reversing the movement of glass below said outlet by periodic upward movement of an implement 60 in adhesive contact with the glass, to form successive suspended gathers of the glass beneath the outlet, periodically accelerating the discharge by the periodic alternate downward movements of said implement to 65 compensate for the attenuation of the upper portion of each suspended gather, and shearing a mold charge from each suspended gather after acceleration and during the retarding and reversing operation by means 70 of shear blades spaced below the outlet and meeting in axial alignment therewith.

32. The method of producing and shaping mold charges of molten glass, which comprises periodically discharging molten 75 glass downwardly through an outlet and past a severing plane spaced below the outlet, severing the glass by thrusting shear blades through the glass at a speed which decreases during the severing operation, lifting the glass adjacent to the severing plane during the severing operation, thereby imparting a conoidal shape to the stub of glass remaining above the severing plane after severance, and initiating a new 80 discharge of glass having at its lower end the said conoidal-shaped stub.

CERTIFICATE OF CORRECTION.

Patent No. 1,631,107.

Granted May 31, 1927, to

KARL E. PEILER.

It is hereby certified that error appears in the printed specification of the above numbered patent requiring correction as follows: Page 1, line 68, for the word "together" read "gather"; page 14, line 46, claim 30, after the word "below" insert the article "the"; line 47, strike out the words "past the shearing level" and insert the same to follow after the word "outlet" in line 48, and line 47, after the word "lifting" strike out the article "the"; and that the said Letters Patent should be read with these corrections therein that the same may conform to the record of the case in the Patent Office.

Signed and sealed this 12th day of July, A. D. 1927.
